DESIGN FOR A COMBINED ARMORED TRACTOR AND SEMITRAILER

Robert G. Le Tourneau, Peoria, Ill., assignor to
R. G. Le Tourneau, Inc., a corporation of California

Application June 14, 1940, Serial No. 93,002

Term of patent 14 years

To all whom it may concern:

Be it known that I, Robert G. Le Tourneau, a citizen of the United States, residing at Peoria, in the county of Peoria and State of Illinois, have invented a new, original, and ornamental Design for a Combined Armored Tractor and Design for a Combined Armored Tractor and Semitrailer, of which the following is a specification, reference being had to the accompanying drawing, forming a part thereof.

In the drawing:

Figure 1 is a side elevation of a combined armored tractor and semitrailer,

Figure 2 is a plan view of the unit,
Figure 3 is a rear end view of the unit, showing my new design.

The appearance of the unit on the side opposite that shown in Fig. 1 is substantially identical with that shown in said figure.

I claim:

The ornamental design for a combined armored tractor and semitrailer, as shown and described.

ROBERT G. LE TOURNEAU.
